UNITED STATES PATENT OFFICE.

LEE J. WESTFALL, OF OMAHA, NEBRASKA.

INCUBATOR-ALARM.

1,001,719.

Specification of Letters Patent. Patented Aug. 29, 1911.

Application filed May 8, 1911. Serial No. 625,722.

To all whom it may concern:

Be it known that I, LEE J. WESTFALL, a citizen of the United States, residing at Omaha, in the county of Douglas and State 5 of Nebraska, have invented certain new and useful Improvements in Incubator-Alarms, of which the following is a specification.

This invention relates to improvements in incubator alarms, and has for its object to 10 provide a device for use in connection with an incubator for sounding an alarm when the temperature within the hatching chamber is unduly increased or diminished.

Incubators are generally provided with a 15 thermostat and a damper for regulating the temperature, movement of the heated air from the heating lamp being under control of the arm of the thermostat for this purpose, so that, approximately, a temperature 20 of 103 degrees F. may be maintained; and the temperature of the hatching chamber should not vary more than two degrees from this standard. The control thus provided, however, is not adequate, since sudden 25 changes in the weather, the blaze of the lamp or other accidental causes may effect a variation of several degrees from the required range of temperature.

The invention provides an alarm to be 30 automatically sounded whenever the temperature is less than 101 or greater than 105 degrees F., and means for adjustments are provided so that the alarm will be sounded at other predetermined or specific degrees 35 of temperature, as may be desired.

The invention has reference, particularly, to a device which will consist of few and simple parts so that it may be constructed economically, and will be convenient and 40 reliable in use.

With these objects in view the invention presents a novel construction, combination and arrangement of parts as described herein and claimed, and as illustrated in the 45 drawing, wherein,—

Figure 1 is a broken away view showing, in plan, a part of the hatching chamber of an incubator, and an alarm mounted thereon. Fig. 2 is a vertical, side view of the device. 50 Fig. 3 is a view of the opposite side to that shown in Fig. 2. Fig. 4 is a view somewhat similar to Fig. 2, a part of the casing being broken away and the yoke shown in section. Fig. 5 is an enlarged, broken away, 55 front view of the device.

Referring now to the drawing for a more

particular description, numeral 6 indicates the wall of an incubator, and 7 the heating drum therefor, said drum having an aperture 20 formed in its upper end, and provided 60 with a conducting pipe 8 for the passage of heated air within the hatching chamber 9 of the incubator. The disk of a thermostat is indicated at 10, the movable arm of the thermostat being indicated at 11. Said 65 arm is pivotally mounted at 12 upon bracket 13 mounted at 14 upon the wall of the incubator. The parts thus described are old and in general use, and therefore they require no particular description, except it 70 may be stated that the construction of the thermostat is such that its arm may have a swinging movement in a vertical plane from the effects of heat which passes within the incubator through pipe 8. Arm 11 of the 75 thermostat projects outwardly of the incubator through an aperture (not shown) formed in wall 6. Upon the top of drum 7 is indicated the closure-cap 15. At 16 is indicated a lever pivotally mounted at 17 80 upon the drum, one of its ends being pivotally mounted at 18 upon arm 11 of the thermostat, its opposite end being pivotally mounted, as indicated at 19, upon cap 15. Since these parts are so well known they 85 require no particular description, except to state that arm 11 operates as a controlling lever for the damper. When disk 10 is expanded and is elevated from excessive heat, the inner portion of said arm will 90 be elevated, the outer end being lowered and causing lever 16 to swing, and thereby elevating or lifting cap 15 from the top of the drum to allow the escape of heat from 95 said drum. When cap 15 has been elevated, heat will pass from the drum to the atmosphere through opening 20, formed in the top of the drum. The operation of the thermostat is such that, when the temperature of the hatching chamber, for any reason, has become cooled in an excessive degree, disk 10 will be lowered. The outer end of arm 11 will thereupon be elevated to cause cap 15 to be lowered and effecting a 100 closure of opening 20.

It is well known that the temperature of the hatching chamber should be maintained at from 101 to 105 degrees, and the adjustments of thermostats usually employed provide for maintaining the temperatures within this range. By reason of accidents, however, the supply of heat may be cut off, or 105

from other causes the thermostat may fail to provide the required control, and therefore an alarm should be provided, now to be described, to be automatically sounded 5 whenever the temperature within the hatching chamber approaches a dangerous extreme of heat or cold.

At 21 is indicated a casing which may be constructed to advantage of sheet metal, 10 open at its ends and having upright, parallel sides 22 and 23 bent transversely at their front ends to provide flat, reinforcing flanges 24, said flanges being disposed in horizontal alinement. Upon wall 22 may 15 be mounted an alarm bell 25 of any ordinary hammer-and-going-type, the alarm being sounded by a movement of its lever or operating-arm 26.

At 27 is indicated an aperture formed in 20 wall 22 adjacent to the bell; and, disposed transversely of and pivotally mounted upon the casing is tripping-arm 28, the outer end of said arm being adapted to engage arm 26 with its inner end disposed above the bottom of the casing; and if the inner end of arm 28 is depressed, arm 26 will be moved or released, and the bell will be sounded.

Pivotaly mounted at 29 near the bottom and near the front end of the casing, is the 30 tilting-bar 30, and when disposed vertically, said bar may bear upon the rear edge of the transverse platform 31, said platform being secured upon and near the front parts and extending between sides 22 and 23, near 35 their upper ends, and the platform tends to sustain the sides parallel and in rigid relation. Bar 30 is so mounted that, normally, it will remain in a vertical position, but if swung rearwardly a limited extent out of 40 equilibrium, it will fall or swing substantially 90 degrees, by its own weight, to depress the tripping-arm 28, for sounding the alarm.

At 31' is indicated a lower contact-finger, 45 projecting forwardly of flanges 24 and normally disposed horizontally, said finger being rigid with its shaft 32, said shaft being pivotally mounted in the sides of the casing. Finger 31' is provided with a rearwardly extending lever 33 adapted to bear upon the tilting-bar, and disposed below said finger. A weight 47 is provided for shaft 32, and by reason of the construction and the weighted shaft, when finger 31' is 50 disposed horizontally, lever 33 will make contact with tilting-bar 30 when said bar is disposed in an upright position; and if finger 31' is swung downward, lever 33 will cause bar 30 to fall or swing rearwardly to 55 depress arm 28.

I employ a rigid operating-arm 35, disposed above finger 31' at the front of and transversely of the casing, and by means of set screw 36 said arm 35 may be rigidly 60 secured upon arm 11 of the thermostat; and

it will be seen that if said arm 11 is lowered to a sufficient extent, operating-arm 35 will engage contact-finger 31', to depress it, and thereby will cause bar 30 to fall or swing rearwardly for sounding the alarm.

By means of set-screw 36 an adjustment 70 may be made of the mounting of operating-arm 35 upon arm 11, so that arm 35 may, normally, be disposed nearer to or farther from contact-finger 31', as may be desired. 75 In practice, the adjustment is such that a decrease of two degrees in temperature will not cause a contact of these parts, but that the contact will be made and the alarm will be sounded if the decrease in temperature 80 is as much as three degrees.

At 37 is indicated a yoke mounted slidably between sides 22 and 23 of the casing, below platform 31, said yoke preferably having transversely formed bases or terminals 38 adapted to have seatings in longitudinal grooves or channels 39 formed in flanges 24. The yoke is provided with a threaded stem 40 which may traverse the platform. A spring 41 is disposed upon the upright stem 40 between the yoke and the platform, said spring normally tending to move the yoke downward from the platform, and by use of the keeper or nut 42, the yoke may be disposed at greater or 95 lesser distances from the platform, as may be desired.

At 43, above operating-arm 35, is indicated the upper contact-finger; it is rigidly mounted upon horizontal shaft 44 said shaft 100 being pivotally mounted in the arms of the yoke. Shaft 44 is provided with the weight 45 and with an upwardly and rearwardly projecting lever 46.

The adjustment of parts is such that the 105 weight 45 will normally dispose contact-finger 43 in a horizontal position, with lever 46 bearing lightly upon the surface of bar 30; and in practice a vertical adjustment of the yoke is made, so that, when arm 35 110 moves upwardly it will engage contact-finger 43 if a change of three degrees from normal occurs. The adjustment should be such that contact-finger 43 will not be engaged until a safe degree of temperature 115 has been exceeded.

In operation, when finger 43 is elevated by the upward movement of arm 35, lever 46 will swing rearwardly. The movement of lever 46 will therefore cause bar 30 to 120 fall or swing rearwardly for sounding the alarm.

Having fully described the several parts and their uses, a further explanation relating to operation is not needed.

What I claim as my invention and desire to secure by Letters Patent is,—

In combination with the movable damper-lever of an incubator; a support; a contact-finger pivotally mounted upon the support 130

and movable by the movement of said damper-lever; a yoke vertically adjustable upon the support above said contact-finger; a second contact-finger; said second contact-finger being pivotally mounted upon said yoke and movable by the movement of said damper-lever; a tilting-bar movable by a movement of said contact-fingers, and an

alarm adapted to be sounded by a movement of said tilting-bar. 10

In testimony whereof I have affixed my signature in presence of two witnesses.

LEE J. WESTFALL.
